UNITED STATES PATENT OFFICE.

WILLIAM F. CONKLIN, OF TARENTUM, PENNSYLVANIA, ASSIGNOR TO WEST PENN STEEL COMPANY, OF BRACKENRIDGE, PENNSYLVANIA, A CORPORATION OF NEW JERSEY.

FORE-PLATE FOR ROLLING-MILLS.

1,202,674.

Specification of Letters Patent.

Patented Oct. 24, 1916.

Application filed August 9, 1915. Serial No. 44,388.

To all whom it may concern:

Be it known that I, WILLIAM F. CONKLIN, a citizen of the United States, residing at Tarentum, in the county of Allegheny and 5 State of Pennsylvania, have invented certain new and useful Improvements in Fore-Plates for Rolling-Mills, of which the following is a specification.

My invention consists of an improvement 10 in water cooled foreplates for rolling mills and the like.

It has for its object to provide a foreplate adapted to support the article being rolled in its progress toward the rolls, in such a 15 manner as to reduce the friction, permit removal of waste matter, as scale, etc.; to provide means for supporting the plate during its inward travel toward the rolls by means of a plurality of longitudinal ridges; to so 20 arrange said ridges as to provide a plurality of pairs of ridges at different levels in view of possible sagging of the plate; to provide means for maintaining circulation of a cooling fluid through the plate; and to so construct the plate as to provide ample space 25 between its inner end and the rolls, together with other features of construction and advantage as shall be more fully hereinafter set forth.

Referring to the drawings, illustrating 30 one preferred form of the invention,—Figure 1 is a partial view in elevation of a stand of rolls with the foreplate in position. Fig. 2 is a plan view showing portions of the 35 mill, housings and rolls, and the relative position thereto of the foreplate in position. Fig. 3 is a vertical sectional view taken on the line III. III. of Fig. 1. Fig. 4 is an 40 enlarged sectional detail view of the foreplate, indicated by the line IV. IV. of Fig. 2.

In the drawings, 2, 2, represent the usual 45 housings of a stand of rolls in which are mounted the upper and lower rolls 3, 4, respectively in the customary well-known manner, the rolls in the construction shown being designed for rolling plates or sheets.

My improved foreplate, which is generally indicated by the letter A, is preferably 50 made of a single integral casting having ample area for the support of the somewhat flexible plate or sheet 5 being rolled.

The sheet in the usual operations, which may be of variable width and length, is in-

troduced into the bite of the rolls over the 55 supporting surface of the foreplate by the workmen, either with or without the use of the extension guide B (Fig. 3). Said extension guide is used with extra long sheets, and is designed to be supported by its inner 60 terminals B' in receiving sockets 6, 6, at each outer corner, and by its vertical supporting legs at its outer end, as will be readily understood.

The foreplate is preferably arranged with 65 a slight downward inclination toward the rolls, as clearly shown in Fig. 3, whereby the sheet will be directed inwardly toward the rolls somewhat below their reducing space. The foreplate is supported, for such 70 purpose, by means of an inner cross bar 7, carried by the housings at each end, and at its outer end by supporting brackets 8, 8, also secured to the housings, upon which rest the lateral front wing portions 9 of the 75 foreplate. Said wing portions 9 are on the same general level as and constitute the side members of the plate, extending backwardly between the housings, as indicated at 9', to a point adjacent to the rolls. The middle portion 80 of the foreplate, which is undulating in cross section to provide the supporting ridges, hereinafter described, extends inwardly somewhat beyond said side portions, partly between the upper and lower rolls, 85 thereby providing a support for the sheet as nearly as possible to the bite of the rolls. Between such side portions, the middle body portion of the plate is formed to provide a series of alternating upwardly extending 90 longitudinal ridges or supporting ribs, a, a, b, b, and b', b'. The spaces intervening each pair of the several ridges constitute longitudinal depressions or channels 10, the several ridges and channels all sloping 95 downwardly and inwardly toward the rolls. At intervals, the bottom of each channel is provided with a plurality of perforating outlet openings 11, for the purpose of providing for escape of accumulated scale, lub- 100 ricant, etc., which may be pushed along the channels from the front, falling out through such openings or over the inner ends of the channels. Openings 11 may be arranged as to location and number with a view of best 105 disposing of the waste matter, depending on the material being rolled.

For the purpose of providing a circula-

tion of cooling fluid, as water, the several ridges, a , b , and b' are internally cored, as indicated at 12, providing circulating channels which are connected alternately at front 5 and back respectively by cross cord channels 13 and 14 respectively. The outermost channels 12 are connected at their front portions with supply pipe 15 and an outlet pipe 16 respectively leading from and to any 10 suitable supply and exhaust connections, whereby to provide for ample water circulation.

In the arrangement shown, the ridges a , a , at each side of the middle ridges b , b , extend somewhat above said ridges b and ordinarily constitute the principal supports for a sheet of normal size and stiffness. The intervening ridges b are for the purpose of providing supplemental supports in case of 15 the sagging of the sheets or for comparatively narrow sheets, the outer ridges b' , b' also providing for such supplemental support beyond the ridges a . By this means I provide a minimum number, as a pair, of 20 active skids or supports for plates of any given width, thereby reducing the number of contacting faces.

The outermost ridges b' , as shown, are on substantially the same level as the side shelf 30 portions 9—9', which practically forms a continuation thereof, and I preferably bridge across the outermost channels 10, 10 by extending the level of the side plates inwardly to the top of the ridges b' for a short distance back of the front of the plate, as indicated at 17.

The plate is reinforced underneath by transverse strengthening ribs 18, 19, and 20, 40 the latter of which embrace the supporting bar 7, while rib 19 and rear rib 20 are of sufficient cross section to provide for the coring for the circulation channels 14 and 13.

In order to prevent any scale, lubricant, or other foreign matter which may pass beyond 45 the openings 11 from falling on to the surface of the rolls, and to provide an air gap to prevent the heat of the rolls from being transferred to the foreplate, and also to allow the operator to get a full view of the 50 lower roll, and admit of access thereto, the inner end and side portions of the foreplate are hollowed out at different locations. Thus the central end portion between the two principal ridges a , a , is hollowed out in 55 a somewhat semi-circular form, and preferably sloped for clearance, as at 21. At each outer side of the ridges a , a , the inner corners are concaved, as at 22, 22; and the inner side 60 portions are cut away, providing longitudinal side openings between the plate and the housing, as at 23, 23.

By this construction any foreign matter which may possibly reach the rolls, may be readily observed and removed. This is an 65 especial advantage, because the rolls should

be kept clean and free for the best results in sheet rolling, otherwise the sheets or plates may be damaged.

The foreplate, as thus constructed and used, is adapted to be readily placed in position, or removed, and is mounted entirely upon supports carried by the housings themselves, requiring no additional support or mechanism, other than the supply and exhaust pipes, and the extension guide B, when 75 used.

An especial advantage of the invention is that it reduces the frictional surface and eases the progress of the sheet toward the rolls, the rounded upper surfaces being easily 80 kept lubricated, while the cooling of the plate prevents undue destruction and wear of the lubricant itself.

The invention may be made in various sizes or proportions, or otherwise changed in 85 different details of construction by the skilled mechanic to suit different requirements or adaptations in use, provided all such changes fall within the scope of the 90 following claims.

What I claim is:

1. A foreplate for rolling mills having a series of longitudinal supporting ridges and alternating channels.

2. A foreplate for rolling mills having a series of longitudinal supporting ridges and alternating channels provided with perforating outlet openings.

3. A foreplate for rolling mills having a series of longitudinal supporting ridges and 100 alternating channels, and means providing for water circulation through the body portion of the plate.

4. A foreplate of the class described comprising a middle longitudinal ridged and channelled portion and lateral flat portions.

5. A foreplate of the class described comprising a middle longitudinal ridged and channelled portion and lateral flat portions 110 having laterally extended front supporting portions.

6. A foreplate of the class described comprising an integral casting embodying flat side portions, intervening longitudinal supporting rib portions with intervening channels having outlet openings therethrough, and embodying a continuous longitudinal and transverse fluid circulation conduit.

7. A foreplate for rolling mills having a series of longitudinal supporting ridges and 120 alternating channels, said ridges terminating at different levels.

8. A foreplate for rolling mills consisting of a generally flat body portion having its greatest width at front and successively narrower toward the rear, provided with longitudinal supporting ridges and alternating channels, with central and lateral terminal clearance openings.

9. A foreplate for rolling mills having a 130

series of longitudinal supporting ridges and alternating channels, and provided with concave clearance openings at its inner central and corner portions.

5 10. In combination with the rolls and housings of a rolling mill, a foreplate mounted on the housings in advance of the rolls having a series of longitudinal ridges and alternating channels, and having inner 10 central, corner, and lateral recessed edge portions.

11. In combination with the rolls and housings of a rolling mill, a foreplate mounted on the housings in advance of the 15 rolls having a series of longitudinal ridges and alternating channels, said channels having openings through their bottoms.

12. In combination with the rolls and housings of a rolling mill, a water cooled foreplate provided with a plurality of longitudinal supporting ribs terminating at different levels, a plurality of intervening longitudinal channels, means for passing a circulating current of water through the foreplate, and means for supporting said 20 25 foreplate with relation to the rolls.

In testimony whereof I have hereunto affixed my signature in the presence of two witnesses.

WILLIAM F. CONKLIN.
